UNITED STATES PATENT OFFICE.

ADOLF GRÜNSTEIN, OF BUDAPEST, AUSTRIA-HUNGARY.

APPARATUS FOR STAMPING AND SHAPING DENTAL METAL CROWNS.

No. 828,109.

Specification of Letters Patent.

Patented Aug. 7, 1906.

Application filed June 2, 1904. Serial No. 210,823.

To all whom it may concern:

Be it known that I, ADOLF GRÜNSTEIN, a subject of the King of Austria-Hungary, residing at Budapest, Austria-Hungary, have 5 invented a new and Improved Apparatus for Stamping and Shaping Dental Metal Crowns, of which the following is a full, clear, and exact description.

The present invention consists of an apparatus 10 for stamping and shaping the metal crowns used in connection with dentistry, and comprises the details of construction hereinafter set forth, and particularly pointed out in the claims.

15 This invention has relation to apparatus for stamping and shaping dental metal crowns, and has for its object the provision of novel apparatus whereby metal blanks may be stamped from a sheet and then by a series 20 of steps shaped to the required size and form.

The invention consists of the novel construction, combination, and arrangement of parts hereinafter described and specifically 25 claimed.

I have illustrated my improvements in the accompanying drawings, in which like numerals designate corresponding parts throughout the several views, in which—

30 Figure 1 is a vertical central sectional view of the apparatus constructed according to my invention. Fig. 2 is a front elevation of the same. Fig. 3 is a top plan view of the same. Fig. 4 is a sectional view taken on the line 4 4 of Fig. 2. Fig. 5 is a top plan view, 35 on an enlarged scale, of the matrix-holding plate and part of the base-plate. Fig. 6 is a side elevation of the stamping tool or plate, and Fig. 7 is a fragmentary detail vertical 40 sectional view showing part of one of the dies and the matrix belonging to such die.

The base-plate 1 of the apparatus has a vertical screw-spindle 2, rotatably mounted thereon at the center of the base-plate, and 45 in a recess in said base-plate a revoluble matrix-plate 6 is mounted, which matrix-plate is adapted to be revolved around the spindle 2 as a center, but is not influenced by the threads of the spindle. The matrix-plate 6 is 50 provided with a plurality of suitable matrix-orifices 9 of different sizes. In each of these matrix-orifices is mounted a mold or core 13,

an elastic plate 14 of rubber or the like being placed under each such mold or core.

The base-plate 1 is provided with an orifice 55 15, extending from near the spindle 2 to the front edge of the base-plate, so that if necessary the molds or cores 13 may be pushed out of the orifices 9 from beneath the base-plate.

The spindle 2 is formed with a head 2', in which is mounted a lever 2'', by means of which the spindle may be turned. A stamping-plate 7 surrounds the spindle 2 just below the head 2', and this plate is formed with 60 a series of female dies 10, which are disposed near the edge of the plate and are of varying size and are adapted to receive corresponding male dies 5. The male dies 5 are mounted in an intermediate plate 3, which is 65 mounted on the screw-spindle 2 and is provided with an internal thread to engage the thread of the screw-spindle, so that when the screw-spindle is rotated the said intermediate plate will be moved up and down. 70

A number of hollow standards 8 are interposed between the stamping-plate 7 and the matrix-plate 6, and these standards receive bolts 8', which pass through the matrix-plate and the standards and extend through the 80 stamping-plate 7 and carry nuts 8'' on their upper ends.

The standards 8 pass through holes in the intermediate plate 3, these holes being sufficiently large to permit the intermediate 85 plate to be moved up and down without frictional engagement with the standards, and the hollow standards 8 and the bolts 8' serve to sustain the stamping-plate 7 in fixed position relatively to the matrix-plate 6. 90

The intermediate plate 3 is preferably formed in the manner clearly shown in Fig. 1 of the drawings—that is, it is composed of two plates laid one on top of the other and secured together by a nut 3' at the center, which nut is secured in position and attached to both plates in any suitable manner—such, for instance, as by making the holes at the centers of the plates in which the nut seats a tight fit or by shrinking the plates upon the nut or in any other well-known or desired manner.

The purpose of forming the intermediate plate in two sections, as above described, is

to facilitate the boring and tapping of the holes in the upper plate, which receive the male dies 5, and the boring of the holes in the lower plate, which receive certain dies and 5 die-holders hereinafter described.

- The intermediate plate carries a series of downwardly-extending dies 4, each of which is adapted to engage with one of the matrices of the matrix-plate 6. In addition to the 10 dies 4 the intermediate plate 3 carries a die-holder 16, which is adapted to receive successively a series of dies, each of which is formed with a countersunk lower end of such configuration on its lower end so as to form the 15 tops of the different crowns in a variety of shapes. One of these dies 16' is shown in position in the holder 16 in Fig. 1 of the drawings, and it is held in position in the holder by a thumb-screw 16".
- 20 The dies 4 are each formed with a recess or die-cavity 4' on its lower end, so that each die will when brought down by the movement of the intermediate plate 3, so as to enter its appropriate orifice 9 in the plate 6, 25 fit over the matrix 13 in that orifice, the recess 4' in the die 4 being somewhat larger than the matrix over which it fits, so as to permit of the metal disk which is to form the crown being pressed down over the matrix.
- 30 In Fig. 7 of the drawings a partially-formed crown 13' is shown in position over the matrix 13 and within the recess 4' of the die 4. The plate 6 is provided with a plurality of half-round recesses 11 in its periphery, and 35 the base-plate is provided with a single recess 12 at one part of its circumference, which recess 12 successively registers with the recesses 11 as the plate 6 is revolved, the recess 12 and one of the recesses 11 serving to receive 40 the pin 12', which serves to lock the plate 6 in any one of the several positions necessary to bring the orifices 13 successively under the tool-holder 16 or under their appropriate dies 4.
- 45 The screw-spindle 2 is sustained against longitudinal movement by a shoulder 17 on the screw-spindle and by a nut 17', that is fixed on the screw-spindle under the base-plate 1, this construction of parts permitting 50 the screw-spindle to revolve freely and at the same time preventing any longitudinal movement of the same.

The parts being constructed and arranged as above described and as shown in the drawings, the apparatus is operated in the following manner: The pin 12' being removed, the plates 6 and 7 are adjusted with the required matrix-orifice 9 and die 4 in front of the operator, and the plate 6 is then locked to the 60 base-plate by replacing the pin 12' in the recess 12 and the registering recess 11. The metal plate from which the blanks are to be

struck is then inserted between the die and the matrix-orifice, which are at the front of the apparatus, and by turning the screw-spindle 2 the die is lowered, whereby the metal plate is cut out and roughly formed over the matrix 13 in the matrix-opening. The screw-spindle is then turned in the reverse direction, so as to elevate the intermediate plate 3 and the dies 4, and the appropriate die having been selected and fitted in the die-holder 16 the plate 3 is again lowered by turning the screw-spindle, and the top of the roughly-formed crown is given the 75 desired contour by the action of the selected die 16'. The intermediate plate 3 is again raised by turning the screw in the proper direction, and the roughly-formed crown is removed from the matrix 13 and is placed on 80 top of one of the male dies 5, and the plate 3 is then raised by turning the screw-spindle, and the crown is forced through the female die 10, and thereby formed to final shape.

Having described my invention, I claim— 85

1. A device for forming and shaping dentistry-crowns, consisting of a base-plate, a matrix-plate mounted on said base-plate and having matrices arranged therein near its periphery and an upper stationary plate having orifices of different diameters around its periphery, a central vertical spindle having a screw-thread thereon and an intermediate plate having an internal thread to engage said spindle and having a series of stamps on 90 its upper surface to engage the orifices of the upper plate and a series of dies on its lower surface to engage the matrices of the lower plate substantially as described.

2. A device for forming and shaping dental 100 crowns, consisting of a base-plate, a matrix-plate rotatably mounted on said base-plate, said matrix-plate having a series of matrix-openings arranged around its center, a vertical screw-spindle mounted to rotate in said 105 base-plate, an upper plate connected to said matrix-plate by vertical standards and having a series of orifices therein, means for locking the matrix-plate to the base-plate at a plurality of positions, an intermediate plate 110 mounted on said vertical standards and having a series of upwardly-extending stamps corresponding to the orifices in the upper plate, and a series of depending dies corresponding to the matrices in the matrix-plate, 115 said intermediate plate having an internal thread to engage the said spindle, substantially as described.

3. A device for forming and shaping dental 120 crowns consisting of a base-plate, a rotary matrix - plate mounted thereon, a screw-threaded spindle rotatably mounted at the center of said base-plate, an upper stationary plate, a series of vertical standards connect-

ing said upper plate to said matrix-plate, a series of dies arranged in the matrices of the matrix-plate, an intermediate plate having an internal thread to engage said spindle and 5 having a series of stamps on its upper surface, said upper plate being provided with a series of orifices to receive said stamps, a series of depending dies carried by said intermediate plate to engage the said matrices, a die-
holder depending from said intermediate

plate and adapted to receive dies and means for locking said matrix-plate against rotation on said base-plate, substantially as described.

In witness whereof I have hereunto set my 15 hand in presence of two witnesses.

ADOLF GRÜNSTEIN.
